(57) **CLAIM**

The ornamental design for a bottle and cap, as shown and described.

DESCRIPTION

FIG. 1 is a perspective view showing my new design;

FIG. 2 is a side view thereof, the design having six-sided symmetry except for the unclaimed environment shown in broken lines; and,

FIG. 3 is a top view thereof.

The bottom is flat and devoid of surface ornamentation.

The broken lines shown in the drawings are for illustrative purposes only and form no part of the claimed design.
